2,330,915

REFRIGERATING APPARATUS

Lawrence A. Philipp, Detroit, Mich., assignor to
 Nash-Kelvinator Corporation, Detroit, Mich.,
 a corporation of Maryland

Original application August 23, 1940, Serial No.
 353,924. Divided and this application July 18,
 1941, Serial No. 403,027

2 Claims. (Cl. 62—125)

This invention relates to refrigerating apparatus, and more particularly to household refrigerators.

The present application is a division of my copending application Serial No. 353,924, filed August 23, 1940, for Refrigerating apparatus.

Another object of my invention is to provide a primary system including two spaced apart refrigerant evaporators separated by a pressure differential device, and to utilize one of the said evaporators for condensing evaporated refrigerant in a secondary refrigerating system.

Further objects and advantages of the present invention will be apparent from the following description, reference being had to the accompanying drawing, wherein a preferred form of the present invention is clearly shown.

In the drawing:

Fig. 1 is a fragmentary view of my improved refrigerator showing particularly an ice making primary evaporating element and a heat exchange connection between primary and secondary systems;

Fig. 2 is a front view of the element shown in Fig. 1; and

Fig. 3 is a diagrammatic view of a refrigerating system used for refrigerating the cabinet shown in Fig. 1.

Referring to the drawing, there is shown a cabinet, designated in general by the numeral 20. The cabinet includes an inner metallic liner 22 which defines a food storage compartment, designated by the numeral 24. The food compartment 24 is refrigerated by a primary refrigerating system 30 aided by a secondary refrigerating system 34.

The primary refrigerating system 30 includes an ice making evaporating element 40 located in the food storage compartment 24, a condensing unit 44, and a relatively high temperature evaporating element 48. The evaporating element 40 per se is of the type shown and described in detail in my copending application, Serial No. 353,924, filed August 23, 1940, for Refrigerating apparatus, of which the present application is a division. The secondary refrigerating system 34 includes a secondary condensing element 56 secured to the outside of the inner liner 22 and a secondary evaporating element 60 which is preferably attached to the rear wall of the inner liner and extends downwardly to the bottom wall of said liner in the manner shown and described in the above mentioned application.

In accordance with my invention, liquid refrigerant is delivered from condensing element 44 through a liquid supply or small diameter tube 66 to the refrigerant evaporating portion 48. The small diameter tube 66 is the sole control for the flow of liquid refrigerant to the evaporating portion 48. The evaporating portion 48 is secured to plate 70 which is clamped to a plate 74 to which the secondary condensing element 56 is secured. Thus the plate 70 and plate 74 are provided to bring the primary refrigerating system into heat exchange relationship with the condenser of the secondary system and condensing evaporated refrigerant in the secondary system. After the refrigerant leaves the evaporating portion 48 it passes to the evaporating element 40 through a fixed restriction 80. The fixed restriction maintains a pressure differential between the evaporating portion 48 and the evaporating element 40 so as to maintain a higher pressure in the element 48. The condensing unit 44 functions in the well known manner.

Although only a preferred form of the invention has been illustrated, and that form described in detail, it will be apparent to those skilled in the art that various modifications may be made therein without departing from the spirit of the invention or from the scope of the appended claims.

I claim:

1. Refrigerating apparatus comprising a primary refrigerating system including two refrigerant evaporators connected in series relationship, means connected in the system between said two evaporators for maintaining the first one of said evaporators to receive refrigerant at a higher temperature than the other, and a secondary refrigerating system including an evaporator and a condenser associated with said higher temperature evaporator.

2. Refrigerating apparatus comprising a primary refrigerating system including two refrigerant evaporators connected in series relationship, means connected in the system between said two evaporators for maintaining a pressure differential between said evaporators and a secondary refrigerating system including an evaporator and a condenser associated with the first one of the evaporators of the primary system to receive refrigerant.

LAWRENCE A. PHILIPP.
